(57) **CLAIM**

The ornamental design for a handle for machine elements as shown and described.

DESCRIPTION

1. Handle for machine elements

- 1.1 : Front
- 1.2 : Right
- 1.3 : Bottom
- 1.4 : Left
- 1.5 : Top
- 1.6 : Back
- 1.7 : Perspective

Handle for machine elements composed of a base formed by a series of concentric coaxial cylinders internally holed and a main body composed by a cylindrical stem, coaxial to said base on the top of which a gripping element abuts substantially perpendicular. Said gripping element is provided with ergonomic elements for the accommodation of fingers in the lower surface. On the top surface of the cylindrical stem a circular cap is provided. The broken lines in the drawings show portions of the handle that form no part of the claimed design.

1 Claim, 7 Drawing Sheets
